[57] CLAIM

The ornamental design for an armored car, as shown and described.

DESCRIPTION

FIG. 1 is a perspective view of an armored car showing my new design.

FIG. 2 is an enlarged front perspective view thereof.

FIG. 3 is a side elevation view thereof;

FIG. 4 is an elevation view of the other side thereof;

FIG. 5 is an enlarged rear perspective view thereof, it being understood that the tires have been fragmentarily shown for ease of illustration; and

FIG. 6 is a top plan view thereof.

FIG. 3

FIG. 4

FIG. 2

FIG. 6

UNITED STATES PATENT AND TRADEMARK OFFICE
CERTIFICATE OF CORRECTION

PATENT NO. : D256,225

DATED : August 5, 1980

INVENTOR(S) : Russell E. Bauer

It is certified that error appears in the above-identified patent and that said Letters Patent is hereby corrected as shown below:

The title page and the three sheets of drawings should be deleted to insert the attached therefor.

Signed and Sealed this

Twenty-fourth Day of February 1981

[SEAL]

Attest:

RENE D. TEGTMEYER

Attesting Officer

Acting Commissioner of Patents and Trademarks
